UNITED STATES PATENT OFFICE.

EDWIN FARGO, OF WILSON, PENNSYLVANIA.

UNCOILING APPARATUS.

1,099,695.

Specification of Letters Patent.

Patented June 9, 1914.

Original application filed April 17, 1913, Serial No. 761,737. Divided and this application filed November 25, 1913. Serial No. 802,905.

To all whom it may concern:

Be it known that I, EDWIN FARGO, a citizen of the United States, residing at Wilson, in the county of Allegheny and State of Pennsylvania, have invented certain new and useful Improvements in Uncoiling Apparatus, of which the following is a specification.

My invention relates to improvements in apparatus for coiling or reeling metal, in the form of flat sheets or strips, and relates particularly to mechanism for uncoiling or unwinding a tight compact roll, for delivery to the loose winding machine.

Ordinarily, sheet metal, or as it is known, "flat" metal is wound in tightly compacted rolls or bundles which have to be first unrolled or unwound and then re-rolled by hand or otherwise, for the purpose of providing sufficient looseness in the roll to admit of exposure of all the surfaces and successive pickling operation.

The present application forms a division of my original application filed April 17, 1913, Serial No. 761,737, in which I have shown and described the coiling apparatus, with which the uncoiling apparatus of the present application is combined, and with which it forms a co-operating part. The present invention is therefore illustrated as used in connection with the coiling apparatus.

In the drawings, illustrating one preferred form of the invention, Figure 1 shows in side elevation a complete apparatus embodying both the coiling and uncoiling mechanism. Fig. 2 is a vertical sectional longitudinal view through the uncoiling apparatus, indicated by the line II, II, of Fig. 3. Fig. 3 is a transverse sectional view on the line III, III, of Fig. 1.

The metal, which is to be loosely coiled or wound for the purpose of exposing its surface to the pickling operation, is usually first wound or rolled in a compact bundle or coil 2 which may be placed within a suitable holder 3 having removable side portions 4, 4, hinged at 5, 5, and brought together at the top and there held by any suitable latch device 6, from which the strip 7 of metal is drawn outwardly through slot 8 for introduction to my improved coiling machine. The coil 2, depending on its width, is wound upon a supporting drum 55 or core 9 having additional sections 9' for

increasing or reducing its width, and a supporting shaft 10, the ends of which rest in and may roll along supporting trackways 11 in the upper edge portion of casing 3. A supplemental adjustable intervening support 12 may also be provided, which at the same time acts to space the cores 9 and 9' apart. The sides 4 when open rest on supporting brackets 13, providing for ample clearance to the interior.

The coiling machine, shown at the left side of Fig. 1, is substantially the same in construction and mode of operation as illustrated and described in my prior application above referred to. It comprises a casing 14 having a generally cylindrical interior of the desired curvature and dimensions to receive and contain the metal strip 7 as it is introduced, and to coil it inwardly into a loosely wound bundle, by the confining effect of the inner surfaces, against which the uncoiling or advancing end portion of the strip engages. The casing 14 is provided with an adjustable inner wall section 18, pivotally mounted at 20, and the strip 7 is fed into the interior by means of feed rolls 29, 29, located at each side of an entrance slot, the strip being fed thereby over a supporting roller 30 from casing 3.

The construction and operation of the invention will be readily apparent from the foregoing description. The uncoiling apparatus facilitates the furnishing of metal to the coiling machine, and provides for the various contingencies of operation in apparatus of this type.

The machine is comparatively simple in construction and operation, strong and durable and not liable to get out of order. It may be changed or varied in different details or modified to suit various conditions of use, and all such changes are to be considered as within the scope of the following claims.

What I claim is:

1. A holding housing for coiled flat metal consisting of a main casing having at each side a hinged side and top portion adapted to close the interior, a supporting drum and shaft therefor removably mounted in the casing, and an outlet opening.

2. A holding housing for coiled flat metal consisting of a main casing having hinged side and top portions, a supporting drum consisting of a plurality of sections, a shaft

therefor removably mounted in the casing, and an outlet opening.

3. Uncoiling apparatus comprising in combination a main base and housing provided with adjustable covering portions, a supporting drum pivotally mounted within the housing, and an adjustable spacer therefor.

4. Uncoiling apparatus comprising in combination a main base and housing provided with adjustable covering portions hinged to each side of the housing, means for locking the top portions together, and a supporting drum pivotally mounted partly within the housing and partly within the covering portions.

5. Uncoiling apparatus comprising in combination a main base and housing provided with adjustable covering portions, means for locking the top portions together, and a plurality of supporting drum sections pivotally mounted within the housing.

6. In an uncoiling apparatus for sheet metal strips, the combination of a housing

having a semi-cylindrical interior, longitudinally divided upper portions therefor hinged to the sides of the housing and providing when closed an outlet slot for the strip, and removable supporting drum mechanism rotatably mounted within the housing between its lower and upper portions.

7. In an uncoiling apparatus for sheet metal strips, the combination of a housing having a semi-cylindrical interior, longitudinally divided upper portions therefor hinged to the sides of the housing and providing when closed an outlet slot for the strip, removable supporting drum mechanism rotatably mounted within the housing between its lower and upper portions, and supporting brackets at each side of the housing for the hinged upper portions.

In testimony whereof I hereunto affix my signature in the presence of two witnesses.

EDWIN FARGO.

Witnesses:

C. M. CLARKE,
FRED'K STAUB.
